Primary Examiner — Garth Rademaker*Assistant Examiner* — Samantha Q Lawrence(57) **CLAIM**

The ornamental design for a liquid applicator body, as shown and described.

DESCRIPTION

FIG. 1 is a front perspective view of a liquid applicator body, showing the new design;

FIG. 2 is a rear perspective view thereof;

FIG. 3 is a top plan view thereof, the bottom plan view being a mirror image of the top plan view;

FIG. 4 is a left side elevational view thereof, the right side elevational view being a mirror image of the left side elevational view;

FIG. 5 is a front elevational view thereof;

FIG. 6 is a rear elevational view thereof; and,

FIG. 7 is a front perspective view thereof showing the liquid applicator body with an absorbent member, the absorbent member shown in broken lines.

The broken lines showing an absorbent member in FIG. 7 illustrate environment which forms no part of the claimed design. Other broken lines shown in the drawing figures illustrate portions of the liquid applicator body that form no part of the claimed design.

1 Claim, 4 Drawing Sheets---
